(57) **CLAIM**

The ornamental design for a bottle with cap, as shown and described.

DESCRIPTION

FIG. 1 is a perspective view of a bottle with cap of the present invention;

FIG. 2 is a side view of the bottle with cap of FIG. 1;
FIG. 3 is the other side view of the bottle with cap of FIG. 1;

FIG. 4 is a rear view of the bottle with cap of FIG. 1;
FIG. 5 is a front view of the bottle with cap of FIG. 1;
FIG. 6 is a top plan view of the bottle with cap of FIG. 1;
and,

FIG. 7 is a bottom plan view of the bottle with cap of FIG. 1.

The broken lines represent the boundary of the claim and form no part of the claimed design.

1 Claim, 5 Drawing Sheets
